UNITED STATES PATENT OFFICE

HARRY H. SAWYER, OF RIDLEY PARK, ASSIGNOR OF ONE-HALF TO THE THACKARA MANUFACTURING COMPANY, OF PHILADELPHIA, PENNSYLVANIA.

CEILING-PLATE FOR ELECTRIC LIGHTS.

SPECIFICATION forming part of Letters Patent No. 417,685, dated December 17, 1889.

Application filed July 3, 1889. Serial No. 316,393. (No model.)

To all whom it may concern:

Be it known that I, HARRY H. SAWYER, a citizen of the United States, residing at Ridley Park, in the county of Delaware and State 5 of Pennsylvania, have invented a new and useful Improvement in Ceiling-Plates for Electric Lights, which improvement is fully set forth in the following specification and accompanying drawings—

10 My invention consists of a plate having openings for electric wires and an opening for an insulating-disk, the latter being provided with a shoulder on which said plate rests and sustained by a pipe which is in contact with said disk, the advantages being 15 hereinafter set forth.

Figure 1 represents a face view of a ceiling-plate for an electric light embodying my invention. Fig. 2 represents a vertical section 20 thereof on line $x-x$, Fig. 1.

Similar letters of reference indicate corresponding parts in the two figures.

Referring to the drawings, A designates a ceiling-plate, which, excepting the features of 25 my invention applied thereto, is of usual construction.

B designates a pipe, rod, or support of an electric light, the same passing through said plate A. Within the central opening of the 30 plate A is fitted an annulus or disk C, of insulated material, through which pass the electric wires D and said pipe or rod B. It will be seen that the plate A is insulated from the wires D, and also from the rod or pipe B.

35 Openings are formed in the disk for the passage of wires, and additional openings may be made therein should the number of wires be increased.

It is well known that heretofore ceiling-plates have been pierced for the passage of 40 electric wires therethrough; but said wires, owing to their contact with the edges of the openings in said plates, have been liable to be cut or abraded, thus producing short circuits, which are dangerous owing to their 45 liability to occasion fire around the plates. This is prevented by the provision of the insulator on the ceiling-plate, the same being of annular form to allow the rod or pipe of the light and the wires to pass through the same without affecting the nature of either part.

The insulator and plate are held in position by the casing-pipe E, the upper end whereof has the insulator resting upon it, the plate resting upon a shoulder F on the insulator, it 55 being seen that as the plate is supported on the shoulder of the disk, and the latter sustained by the pipe whose end forms a shoulder against which the disk abuts, said plate and disk are nicely held in position.

Having thus described my invention, what I claim as new, and desire to secure by Letters Patent, is—

The combination of the electric-light support B, with the surrounding ceiling-plate A, 65 the insulating-disk C, fitted in the central opening of the ceiling-plate and having the shoulders F on which the ceiling-plate rests, and openings through which pass the electric wires D, and the casing-pipe E, surrounding 70 the electric-light support B and supporting the insulating-disk, substantially as described.

HARRY H. SAWYER.
